[57] CLAIM

The ornamental design for upright telephone stand, as shown and described.

DESCRIPTION

FIG. 1 is a front and right side perspective view of an upright telephone stand showing my new design;

FIG. 2 is a left side elevational view thereof;

FIG. 3 is a rear elevational view thereof;

FIGS. 4 and 5 are respectively bottom and top plan views; and

FIG. 6 is a right side elevational view thereof.

The broken line showing of telephone handset and cord in FIGS. 1, 2, 4, 5 and 6 is for illustrative purposes only and forms no part of the claimed design.

FIG. 1

FIG. 2

FIG. 3

FIG. 4

FIG. 5

FIG. 6
